UNITED STATES PATENT OFFICE

HOWARD L. KRATZ, OF PHILADELPHIA, PENNSYLVANIA, ASSIGNOR TO HUGH LYONS
& COMPANY, OF LANSING, MICHIGAN, A CORPORATION OF MICHIGAN

DESIGN FOR A COMBINED BASE AND STANDARD FOR A DISPLAY STAND

Application filed January 18, 1932. Serial No. 42,525. Term of patent 3½ years.

To all whom it may concern:

Be it known that I, HOWARD L. KRATZ, a citizen of the United States, residing at Philadelphia, in the county of Philadelphia, and State of Pennsylvania, have invented a new, original, and ornamental Design for a Combined Base and Standard for a Display Stand, of which the following is a specification, reference being had to the accompanying drawings, forming a part thereof.

In the drawings:

Figure I is a side elevation of a combined base and standard for a display stand, showing my new design; and

I claim:

The ornamental design for a combined base and standard for a display stand, as shown.

In testimony whereof he has affixed his signature.

HOWARD L. KRATZ.
